(57) **CLAIM**

The ornamental design for a wall-mount for soap dispensers, as shown and described.

DESCRIPTION

FIG. 1 is a perspective view of a wall-mount for soap dispensers, illustrated with soap dispensers, showing my new design;

FIG. 2 is an exploded perspective view of the wall-mount for soap dispensers, illustrated with a soap dispenser;

FIG. 3 is a perspective view of the wall-mount for soap dispensers;

FIG. 4 is a front elevational view of the wall-mount for soap dispensers;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken line showing of soap dispensers is for the purpose of illustrating environmental structure and form no part of the claimed design.
